FUEL PUMP DIAPHRAGM MOUNTING

Wade Lamb, Detroit, Mich., assignor to F. L. Jacobs Co., Detroit, Mich., a corporation of Michigan

Application January 20, 1950, Serial No. 139,555

1 Claim. (Cl. 137—791)

1
The present invention relates to an improved fuel pump, and more particularly to an improved construction for providing a seal between the diaphragm and a transversely extending valve plate and between flanged complementary casing elements.

In conventional fuel pump constructions including complementary flanged casing members and a plate extending transversely of the casing and supported between the flanges of the casing members, it is necessary that certain of these parts be accurately machined or that one or more separate gaskets be employed, or both.

It is an object of the present invention to provide an improved fuel pump construction which is simple in design, economical of manufacture, and in which an effective seal is provided between the transversely extending plate and the diaphragm and between the complementary casing members without the need for either a separate gasket or accurate machining of any of these parts.

Other and more detailed objects of the invention will become apparent from a consideration of the following specification, the appended claim and the accompanying drawing.

In the drawing:

Figure 1 is a sectional view of a fuel pump construction embodying the present invention; and,

Fig. 2 is a broken enlarged sectional view of that portion of the construction illustrated in Fig. 1, indicated by the circle 2.

It will be appreciated from a complete understanding of the present invention that the improvements thereof may be readily embodied in apparatuses of widely differing types and designs. In an illustrative, but not in a limiting sense, the improvements of the present invention are herein illustrated and described as embodied in a fuel pump adapted for use on a gasoline internal combustion engine.

Referring to the drawing, the fuel pump there illustrated generally comprises an upper casing member 10 having an inlet chamber 12, an outlet chamber 14 and inlet and outlet valve means generally indicated at 16 for controlling the flow of fuel between these chambers a lower casing member 18, a diaphragm 20 extending transversely of the casing between the upper and lower members 10 and 18 and mechanism generally indicated at 22 for effecting a pumping action of the diaphragm 20. The inlet and outlet valve means 16 illustrated in the drawing is illustrated and described in greater detail in my copending application, Serial No. 16,341, filed March 22, 1948, now Patent No. 2,542,254 granted February

20, 1951, and includes an annular rubber valve element 24 which is supported upon a valve plate 26 extending transversely of the casing. The diaphragm, as will be readily appreciated from a complete understanding of the present invention, may be formed of any suitable flexible and compressible material.

The lower housing member 18 has an annular outwardly projecting flange 28 and the upper casing member 10 has an annular outwardly projecting flange 30 adapted to register with the flange 24 of the lower casing member 18. As best illustrated in Fig. 2, the radially inner portion of the flange 30 on the upper casing member 10 is formed to define an annular recess 32 communicating with the interior of the casing. The valve plate 26 has an annular outwardly extending marginal portion 34 received in the recess 32 and of a thickness slightly greater than the depth of the recess 32, so that the lower surface 36 of the marginal portion 34 is disposed slightly below the lower surface 38 of the flange 30. The marginal portion of the diaphragm 20 is received between the upper surface of the flange 28 formed on the lower casing member 18 at one side, and the lower surface 36 of the marginal portion 34 of the valve plate 26 and the lower surface 38 of the flange 30 on the casing member 10, at the other side.

The flanges 28 and 30 of the casing members 18 and 10 respectively are secured together to effect a firm gripping of the marginal portion of the diaphragm 20, by means of a plurality of screws 40 extending therethrough.

It will now be appreciated that as the screws 40 are tightened, the marginal portion of the diaphragm is first firmly gripped between the lower surface 36 of the valve plate marginal portion 34 and the flange 28, thereby providing an annular seal between the valve plate 26 and the diaphragm 20. Upon further tightening of the screws 40, the diaphragm 20 is firmly gripped outwardly of the valve plate 26 between the flange 28 and the lower surface 38 of the flange 30 to provide annular seals between the casing members 10 and 18 and the marginal portion of the diaphragm 20 gripped between these flanges.

The above described construction permits the casing parts 10 and 18 and the valve plate 26 to be die cast and used without machining since it will be appreciated that it will not be necessary that there be a perfect fit between the valve plate 26 and the upper casing member 10 in which it is mounted. It will also be noted that the above described construction eliminates the necessity of using one or more gaskets.

Although only one specific embodiment of the

invention has been illustrated and described in detail, it will be readily appreciated by those skilled in the art that numerous modifications and changes may be made without departing from the spirit of the invention.

What is claimed is:

In a fuel pump, a casing including a pair of complementary elements having cooperating annular flanges, a diaphragm extending transversely of said casing and having an annular marginal portion received between said flanges, one of said elements having an annular recess formed in the radially inner annular portion of the flange thereof and communicating with the interior of said casing, a plate extending transversely of said casing at one side of said diaphragm and having an annular marginal portion received in said recess and of a thickness slightly greater than the depth of said recess measured at right angles to

5 the surface of said flange engaging said diaphragm, said marginal portion of said plate co-operating with the inner portion of the flange of the other of said elements to grip said marginal portion of said diaphragm therebetween when the latter is gripped between said flanges of said

casing elements, and means for effecting said gripping of the marginal portion of the dia-

phragm between the flanges of said elements.

WADE LAMB.
